ELECTROLYTIC CONDENSER

Harold I. Danziger, New York, N. Y., assignor,
by mesne assignments, to Sprague Specialties
Company, North Adams, Mass., a corporation
of Massachusetts

Application February 9, 1931, Serial No. 514,331

1 Claim. (Cl. 175—315)

My present invention relates generally to electrical condensers, and has particular reference to an electrolytic condenser of improved structure.

This application is a continuation in part, of 5 my co-pending application filed on March 28, 1930, under Serial Number 439,578 now Reissue Patent 19,370.

The general objects of my invention are set forth in my said co-pending application, and lie 10 primarily in the provision of an electrolytic condenser structure which is of simplified nature from the standpoint of manufacture and assembly; which embodies all the requisite qualities which the peculiar characteristics of an electrolytic condenser require; which operates smoothly 15 and efficiently without any likelihood whatsoever of corrosion or the like; which is extremely compact and staunch; and which is peculiarly efficient from the standpoint of mounting the same upon a chassis or supporting platform and 20 making electrical connections thereto.

The various novel and advantageous features of 25 my invention are also outlined in my co-pending application above referred to, and lie in the provision of a condenser of the foregoing character wherein the electrode or electrodes within the 30 container, and all leads and terminals associated therewith, are completely immersed in the liquid or other electrolyte; wherein the structure and arrangement permits the device to be inconspicuously, yet firmly and securely, mounted upon 35 a supporting platform or chassis; wherein the arrangement permits the electrical connection or connections with the submersed electrode or electrodes to be made beneath the platform upon 40 which the condenser is mounted; and wherein the submersed electrode or electrodes are, respectively, supported upon conducting rods which extend out of the container through a wall other than the top wall thereof, and preferably through the bottom wall.

In the structure illustratively exemplified in 45 this application, the container of the condenser, which is of conducting material and is adapted to serve as one terminal thereof, has a top wall which is provided with a vent and a bottom wall which is of insulating material, one of the main advantages lying in the consequent insulation of each electrode-supporting rod which passes downwardly through such bottom wall from the conducting portion of the container. Other features herein illustrated lie in an arrangement whereby a plurality of submersed electrodes may be efficiently mounted in mutually spaced arrangement within the container, each one serving 50

as a terminal complementary to the terminal constituted of the container itself; an arrangement wherein at least one insulating neck or sleeve, serving as a protective sheath, projects into the container from the bottom wall to encircle the 5 lower portion of at least one of the conducting rods; an arrangement whereby such sheath or sheaths may be integrally formed upon the bottom wall; a construction wherein the rod or rods supporting the immersed electrode or electrodes 10 are molded in the bottom wall in a liquid-tight manner; and various arrangements whereby the bottom wall above referred to may be securely associated with the body of the container in a liquid-tight manner.

A particular feature of the structure herein 15 illustrated lies in the arrangement of a depending attachment neck upon the bottom wall, in very much the same manner as such necks are 20 illustrated and described in my aforementioned co-pending application.

I achieve the foregoing objects and advantages, and such other objects and advantages as may 25 hereinafter appear or be pointed out, in the manner illustratively exemplified in the accompanying drawing, wherein—

Figure 1 is a vertical cross-sectional view 30 through an electrolytic condenser mounted upon a chassis and constructed in accordance with my present invention;

Figure 2 is a fragmentary cross-sectional view 35 taken substantially in the same direction as Figure 1, and, more especially, along the line 2—2 of Figure 3, illustrating a modification;

Figure 3 is a cross-sectional plan view taken 40 substantially along the line 3—3 of Figure 2;

Figures 4, 5, and 7 are fragmentary cross-sectional views taken in substantially the same direction as Figure 1, showing further modifications; and

Figure 6 is a cross-sectional view taken substantially along the line 6—6 of Figure 5.

Figure 8 is a view, similar to Figure 2, showing a modified form, combining features of Figures 2 and 7.

In Figure 1, I have shown a container 74 which is 45 preferably tubular in shape and constructed of relatively thin yet strong conducting material, such as sheet aluminum. It is provided with a top wall 121 and a bottom wall 73. In the form illustrated, 50 the top wall 121 has been shown as a separate element or disc held in position by spinning the upper edge of the body of the container into a bead or rim with the marginal edge of the top wall, but it will be understood that this particular 55

arrangement is not essential. Regardless of how the top wall is formed or of what it is constituted, it is provided with a customary small opening or vent 124 which is usually sealed by a rubber cap 5 124' or the like.

Within the container 74 is the liquid electrolyte 125, the upper level of which is usually caused to lie as close as possible to the under-surface of the top wall 121.

10 Immersed in the electrolyte is an electrode 126 which I have shown in the form of a spirally-wound aluminum sheet or strip, this electrode being in the finished condenser coated with a very thin film of electrolytically-deposited material.

15 The electrode is supported upon the core or rod 77 which is of conducting material and which may, if desired, have its upper end engaged with in a spacer 128 or the like. This spacer may be of S-shape or any other suitable configuration, or 20 it may be omitted entirely, its purpose being to maintain the electrode 126 in spaced relationship from the walls of the container 74.

In accordance with my present invention, the 25 rod 77 extends out of the container 74 below the level of the electrolyte 125, and preferably downwardly through the bottom wall 73, no portion of the rod or of the electrode being thereby exposed or likely to be subjected to the corrosive action of the air or gases in contact with the electrolyte. In the form illustrated, the rod 77 is provided with a flange or collar 78; and further down, the lower portion of the rod 77 is exteriorly threaded, as at 80, all for a purpose presently to be described.

30 The rod 77 is insulated from the body of the container 74 by constructing the bottom wall 73 of insulating material, such as hard rubber, bakelite, or any other suitable composition, and the rod 77 passes through this base in a liquid-tight 35 manner. Preferably, the rod is molded into the base.

An important feature of my invention lies in providing an insulating sleeve or neck 76 upon the bottom wall 73, which extends upwardly into 40 the container for a considerable distance and encircles the lower portion of the rod 77 within the container. Preferably, though not necessarily, this sheath or neck is integrally formed upon the bottom wall 73 and the rod is molded therein in the 45 manner illustrated, the flange or collar 78 resting upon the top of this sleeve. A washer 79 is preferably, though not necessarily, employed underneath the collar 78.

50 This upwardly extending sleeve 76 forms a 55 shield for the lower portion of the rod 77 and prevents any sediment which may tend to fall to the bottom of the electrolyte from piling up and ultimately forming a possible short-circuit between the conductive body portion of the container 74 and the rod 77.

The threads 80 on the lower portion of the rod 77 are provided for the purpose of enabling a nut 81 or the like, with or without the assistance of a washer 82 or the like, to engage the rod 77 and 60 to hold the rod securely in position in the contemplated manner, the collar 78 pressing downwardly upon the upper end of the neck 76 and the nut 81 pressing upwardly against the bottom wall 73.

70 In mounting this particular type of construction upon a chassis or supporting platform 83 or the like, the rod 77 and also the nut 81 is permitted to pass downwardly through a suitably prepared opening in the platform 83 so that an electrical connection may be made, as at 85, to the

rod 77. One or more fingers or hooks 84 are secured to the platform 83 in any suitable manner and engage the container 74 at its bottom portion. More particularly, it will be noted that in mounting the bottom wall 73 upon the container 5 74, the latter is spun around the wall 73 so as to provide an annular groove 75 in the exterior of the container 74 close to the bottom thereof. The fingers 84 engage within this groove and thereby serve to grasp the container to hold it in position. 10

Preferably, though not necessarily, the rod 77 is molded within the neck 76, this manner of assembly serving to provide a very secure and liquid-tight joint.

15 It will be noted that the device illustrated in Figure 1 is firmly held in proper position, and yet the upper portion of the platform or chassis 83 is totally devoid of cumbersome fastening devices, hooks, parts, etc.; and, furthermore, that there are no leads of any character extending to any 20 portion of the condenser structure, the connection to the immersed electrode being made beneath the platform 83, as at 85, and the connection to the container 74 being made directly through the platform 83, which is usually of metal. 25 If desired, the fingers 84 may serve to establish this electrical connection, whether the platform 83 is of conductive material or not. As a result of these advantageous features, a number of such condensers may be mounted in close proximity 30 to each other, or they may be individually mounted in a compact relationship to other electrical apparatus, the entire assembly being, obviously, simplified and rendered more compact, attractive, 35 and efficient.

The manner in which the several portions of the structure may be associated with one another may be varied in a number of ways to suit differing requirements. For example, in Figures 2 and 3, I have shown a construction wherein a 40 plurality of electrodes may be immersed in a common body of electrolyte material within a single container. Each individual electrode and its supporting rod is similar to the showing of Figure 1. A relatively larger container 86 is provided with a bottom 87 in the form of an insulating, preferably molded, disc which has a series of upwardly extending necks 88 similar to the neck 76 of Figure 1. Each individual rod, as, for example, the rods 89, 90, and 91, is associated with one of the upwardly extending necks 45 in the manner shown in Figure 1. The entire container may be held down upon a chassis or platform 92 by means of fingers or hooks, such as those which are shown for illustrative purposes at 93. Desired electrical connections may be made beneath the platform 92 to the several 50 projecting ends of the rods 89-91.

Although I have illustratively shown three rods supporting three separate electrodes and 60 arranged at the apices of a substantially equilateral triangle, this arrangement is not absolutely essential, but has proven to be satisfactory and efficient from the standpoint of compactness and general appearance. Obviously the 65 container need not necessarily be circular, and any number of electrodes and supporting rods may be mounted therein in any desired relationship.

Furthermore, the manner of supporting the 70 container upon the platform need not necessarily be of the character illustrated, but where this arrangement is used I have found it to be of advantage to establish electrical connection with the container 86 either through the platform 92, 75

if the latter be of conductive material, or through the fastening devices 93.

The insulating base 81 serves as before to provide a means for establishing secure and liquid-tight joints, an insulation for the various electrode-supporting rods, and a shield or shields for the lower portions of such rods.

Another manner in which a molded insulating piece may be employed in a similar manner is illustrated in Figure 4, wherein it will be noted that the lower portion of the container 96, instead of being spun around the margin of the molded disc, is associated in a suitable manner with a separate annulus, preferably of metal, which is in molded association with the insulating disc. For example, the disc or insulating piece 94 may be initially produced with an annular metallic ring 95 molded or similarly associated with the periphery thereof. This ring may then be spun into engagement with the lower edge of the container 96 in any suitable manner, and, preferably, by the method usually employed in can construction. I have illustratively shown at 97 one manner of clenching the edge of the annulus 95 to the lower edge of the container 96. Fingers or hooks 98 may serve to hold the structure upon a chassis or platform 99, and, if desired, these fingers may engage over the clenched portions 97 instead of in the grooves 100, as illustrated.

The electrode-supporting rod passes through the member 94 in any suitable or desired manner, and I have illustratively shown the same arranged in substantially the same manner as that shown in connection with the rod 11 in Figure 1.

In Figures 5 and 6, I have shown a modification of this structure of Figure 4, an annulus 101 being molded in the periphery of a disc 102, of insulating material, and portions of the annulus are shown as bent downwardly in the form of tabs 103. In mounting the structure upon a platform 104, the latter is provided with suitable slots through which the tabs 103 may be passed. It is then possible by merely bending the tabs, as shown in Figure 5, to clench the under-surface of the chassis 104, whereby this very simple and relatively rapid procedure will serve to hold the structure in secure association with the platform 104.

Obviously, a plurality of rods may be arranged within an insulating member in the manner that the single rods have been shown to be associated with such a member in Figures 4 and 5. The electrical connections to the rod or rods thus mounted and arranged may, if desired, be made at the lower ends of such rods in the manner hereinbefore described. The electrical connections to the container may also be accomplished in the manner hereinbefore mentioned, either by means of a conductive platform or by means of hooks or tabs which secure the container to the platform. For example, in Figure 4, the hooks or fingers 98 serve to establish an electrical connection with the container 96, whether the platform 99 be of insulating material or not. If the platform is not of conductive material, electrical connections may be made to the lower ends of the hooks 98.

Similarly, in Figure 5, the tabs 103 establish connection with the container and condenser and also with the platform 104; and in the event that this platform is not of conductive material, electrical connections may be made to the lower ends of the tabs 103.

In Figure 7, I have illustrated a further modification, similar in many respects to the construction of Figure 1, but illustrating an alternative method of securing the condenser to a platform. A disc or base 105 of insulating material is provided with the inwardly projecting neck 106, as hereinbefore described, and it is also provided with the exteriorly projecting or downwardly depending neck 107 which is preferably threaded exteriorly. The electrode-supporting rod 108 is provided with a shoulder 109 which bears down upon the upper or inner end of the neck 106 with or without the use of a washer 110, and the rod 108 is also exteriorly threaded, as at 111, for the purpose of receiving a nut 112 with or without the use of an interposed washer 113. The nut 112 and the washer 113 are of smaller diameter than the exterior diameter of the neck 107, so that an attachment nut or its equivalent 114 may be engaged with the threads of the neck 107 to hold the entire condenser in position. Here, too, an intermediate washer 115 may or may not be employed, as desired, and such washer may or may not have a portion which projects into the opening 116 in the platform 117 for the purpose of centering the neck 107 in such opening.

In this construction, the container 118 is preferably spun around the edge of the disc or base 105, and it will be noted that its lower edge bears downwardly upon the platform 117. Accordingly, if the latter is of conductive material, electrical connection is established immediately between this platform and the container 118. Electrical connection to the electrode-supporting rod 108 will be made as before at the lower end of this rod, as at 119.

The depending neck 107 is similar in many respects to the depending attachment necks described and illustrated in my co-pending application hereinbefore referred to, and may or may not be interiorly tapered or otherwise constructed in a suitable manner to permit a firm, liquid-tight joint to be made between the rod 108 and this neck. Preferably, in the form illustrated in Figure 7, the rod 108 is molded in position, but it will be understood that this particular arrangement is not essential.

Furthermore, it will be understood that a plurality of rods may be associated with an insulating base in the manner illustrated in Figure 7, so as to provide a plurality of immersed electrodes in a common container, as indicated in Figure 2. In such an event, a series of depending attachment necks 107 may or may not be provided, as desired, and where such attachment necks, other than one, are dispensed with, the electrode-supporting rods are associated with the base in the manner illustratively shown in connection with Figures 1, 4, and 5. An arrangement such as in this paragraph described is illustrated in Figure 8.

Furthermore, the arrangement of the depending neck 107, as shown in Figure 7, may or may not be employed in connection with a construction or constructions similar to those illustrated in Figures 4 and 5.

In general, it will be obvious and readily understood that many modifications and other forms of construction will suggest themselves to those skilled in the art from the examples and the illustrative descriptions given, and I do not mean to restrict myself to any specific form or forms, except as I may be compelled to do so by prior art of which I am not now aware. Regardless of the specific details of construction, it will

be obvious that I have provided an electrolytic condenser structure of highly advantageous and simplified character; one which is not only compact and of workmanlike appearance, but which 5 is capable of rapid and inexpensive assembly, manufacture, and ultimate association with a supporting platform. Furthermore, it will be noted that my structure is extremely efficient from the standpoint of durability and operation, 10 the entire electrode or electrodes being in each case completely immersed in the electrolyte at all times, the likelihood of corrosion being efficiently minimized, if not entirely eliminated, the formation of sediment being suitably guarded against, 15 and the necessity for electrical connections above the level of the supporting chassis being efficiently minimized, if not entirely eliminated.

I have not illustrated any sediment in the 20 figures, since a description of the possible formation of the same will be sufficient for the purpose of explaining the purpose of the upwardly extending sheaths or necks. Any such sediment, if formed at all, is in every case suitably insulated 25 and guarded against any likelihood of short-circuiting the material of the container and the immersed electrode or electrodes.

Furthermore, although I have illustrated the 30 insulating sheath or sleeve and the base of the container as molded elements, nevertheless it will be understood that in certain instances it may be found desirable to provide these members in the form of electroplated members coated with rubber, celluloid, or the like. Also, it will be understood 35 that the upwardly extending insulating necks may, under certain circumstances, be entirely dispensed with or may be made of such various sizes as differing requirements may call for, depending upon the conditions to be en-

countered, the type of electrolyte, and, in general, upon the amount of sediment reasonably to be expected under differing circumstances.

It will also be understood that wherever I have used the term "liquid electrolyte", both in the 5 specification and in the appended claim, I mean to include within this term the various forms of jelly-like or semi-solid electrolytes that are customarily used for this purpose.

In general, it will be obvious that changes in 10 the details herein described and illustrated for the purpose of explaining the nature of my invention may be made by those skilled in the art without departing from the spirit and scope of the invention as expressed in the appended claim. 15 It is therefore intended that these details be interpreted as illustrative, and not in a limiting sense.

Having thus described my invention, and illustrated its use, what I claim as new and desire 20 to secure by Letters Patent is—

In combination with a supporting platform having at least two openings therethrough, an electrolytic condenser comprising an electrolyte container of conductive material adapted to serve 25 as one condenser electrode and having a bottom wall with an aperture therein, said bottom wall being provided with at least one attachment projection along side of said aperture and adapted to extend through one of the platform openings to 30 mount the condenser, means beneath the platform engaging said attachment projection, an electrode within the container including a supporting rod extending down out of the container through said aperture in the bottom wall and 35 through another platform opening.

HAROLD I. DANZIGER.
